DECORATIVE PANEL FOR FURNITURE OR THE LIKE

Henry Klein, 252—05 Culman Ave.,
Little Neck, N.Y. 11362

Filed July 23, 1968, Ser. No. 12,859

Term of patent 7 years

Int. Cl. D6—01

U.S. Cl. D33—1

FIG. 1 is a front elevational view of a decorative panel for furniture or the like, showing my new design, the back being substantially a mirror image thereof;

FIG. 2 is a top plan view;

FIG. 3 is a bottom plan view; and

FIG. 4 is an end elevational view, the opposite end being substantially a mirror image thereof.

I claim:

The ornamental design for a decorative panel for furniture or the like, substantially as shown and described.
